UNITED STATES PATENT OFFICE

2,074,300

LOCOMOTIVE STOKER

Washington T. Capps, Baltimore, Md., assignor
to The Standard Stoker Company, Inc., a cor-
poration of Delaware

Application September 20, 1932, Serial No. 634,074
Renewed January 16, 1937

12 Claims. (Cl. 198—15)

This invention relates to mechanical stokers for locomotives, and particularly to stokers of that type in which coal or like solid fuel is conducted from a fuel bunker on the tender to the 5 firing opening of the locomotive by means of telescopic and jointed feeding means allowing relative movements between the elements of the feeding means on the locomotive and tender to compensate for relative movements of the loco- 10 motive and tender in the travel thereof. More especially the invention relates to a stoker in which the fuel feeding means conveys the fuel to a distributor located in the region of the firing opening and embodying a distributing plate and 15 a steam jet system for impelling the fuel therefrom over the grate area.

An objection to some of the prior locomotive stokers of the type referred to is that they are not universally adapted for use upon locomotives 20 having different deck heights, so that special constructions are necessary in the application of stokers to locomotives having restricted deck heights, and it is one of the objects of my invention to provide a novel and improved construction of stoker which is universally applicable to locomotives having different deck heights, 25 including those of very restricted character.

Another object of my invention is to provide a construction of stoker in which the fuel from the 30 delivery end of the transfer conduit may be entered into one side of the inlet end of the elevating conduit for a lateral feed to the elevating conveyor in the latter conduit instead of delivering the fuel from the transfer conduit to the 35 top of the elevating conduit, whereby the overall height of such conduits may be reduced at their point of union to permit of the application of the stoker to locomotives of restricted deck height, where there is ample horizontal space but only a 40 small amount of vertical space to accommodate such portions of the stoker mechanism.

Still another object of the invention is to provide a mechanical stoker in which the conveyor unit on the tender, the elevating unit on the 45 locomotive and the associated parts of the transfer unit between the first-named units are so constructed that such units may be automatically disconnected without the necessity of unfastening parts thereof by movement of the locomotive 50 away from the tender on the locomotive and tender being uncoupled.

Still another object of the invention is to provide a stoker construction in which the elevating conveyor in the elevating unit or conduit and the 55 primary conveying means for conveying the fuel

thereto from the tender are driven from a primary source of power by separate driving shafts so as to enable said parts to be more flexibly operated and to be arranged to better working advantage on the locomotive, as well as to enable 5 the elevating conveyor to be operated, if desired, at faster speed than the primary conveyor by proper gearing acting in said shafts to prevent congestion of the coal in the elevator unit or conduit.

Still another object of the invention is to provide a stoker having an independently driven conveyor in the elevator unit or conduit together with a fuel door in said conduit whereby fuel may be directly introduced thereinto for hand firing 10 to aid the stoker feed under emergency conditions, and which door is also adapted to permit convenient access to the elevating conduit in 15 making internal repairs, freeing the conduit in case of choking of the coal, and for other like 20 purposes.

Still another object of the invention is to provide a construction of stoker which is not only readily applicable to various types of locomotives of different deck heights, but allows 25 greater flexibility and freedom of motion of the parts of the stoker on the locomotive and tender, greater flexibility and freedom of motion of the conveyor screws or devices, with less liability of 30 undesirable powdering of the fuel or choking of the conveyors by fuel lumps or particles of large size, and which allows greater flexibility of feed control so that a sufficient amount of coal may be supplied to the locomotive firebox at all times.

Still another object of the invention is to provide a mechanical stoker which is simple of construction, reliable and efficient in action, capable of being manufactured, installed and operated at a comparatively low cost, and which, in addition to the other desirable advantages set forth, may 35 be conveniently and economically cleaned and kept in repair.

With these and other objects in view, the invention consists of the features of construction, combination and arrangement of parts, herein-after fully described and claimed, reference being had to the accompanying drawings, in which:—

Fig. 1 is a plan view with parts shown in section of one form of stoker embodying my invention, showing the same in operative relation to a locomotive and tender, parts of which are 50 shown.

Fig. 2 is a side elevation of the stoker with parts shown in section. 55

Fig. 2a is a sectional view showing the steam jet.

Fig. 3 is a cross-section taken substantially on line 3—3 of Fig. 2.

5 Fig. 4 is a cross-section through the gear box or casing.

Fig. 5 is a view similar to Fig. 2 showing another form of stoker embodying my invention.

Fig. 6 is a top plan view mainly of the elevator unit thereof with parts shown in section.

Fig. 7 is a sectional view showing a modified type of distributor.

Fig. 8 is a top plan view of parts shown in Fig. 7.

15 Fig. 9 is an enlarged detail section on line 9—9 of Fig. 2.

Referring now more particularly to Figs. 1, 2, and 3 of the drawings, 1 designates the locomotive frame, 2 the cab deck, 3 the backhead and 20 4 the firing opening of a locomotive, and 5 designates the tender frame, 6 the deck and 7 a portion of the rear wall of the bunker of the tender; while A designates the stoker as a whole, which 25 comprises a conveyor unit A' on the tender and an elevator unit A² on the locomotive, each of which includes complementary parts of a separable transmission connection or unit A³ between such conveyor and elevator units.

The conveyor unit A' on the tender comprises 30 a fixed trough-shaped conduit 8 arranged beneath the fuel bunker and having a longitudinally extending opening in its top through which the fuel feeds thereto by gravity from the bunker. In this conduit or trough 8 is arranged a helical conveyor screw 9 which feeds the fuel forward to the transmission unit A³, from which it is delivered to the elevator unit A². The trough 8 has its rear end disposed in the same longitudinal plane as the central longitudinal plane or axis of the elevator unit A², but extends therefrom forwardly and laterally at a slight angle to such plane, so that its forward end is offset laterally with respect to the vertical central longitudinal plane of the conveyor unit and slightly to one side of such plane, for a purpose hereinafter described. As the elevator unit A² is usually arranged coaxially with and in the vertical longitudinal plane denoted by the line x—x in Fig. 1 bisecting the locomotive and tender, it will be understood that the forward or delivery end of the trough 8 is arranged laterally or to one side of such bisecting plane. The trough 8 is also inclined downwardly and rearwardly at a slight angle and provided 45 at its rear end in its bottom with drain holes 10, whereby water from the coal accumulating in the trough may be freely discharged to prevent it from coming in contact with and damaging the conveyor drive gearing. A guard or housing 50 10^a is provided at the rear of the trough to prevent the coal from being washed out through the drainage holes 10.

As shown, the trough 8 connects at its rear end with a gear box or casing 11 and at its forward end is provided with a rear socket member 12, which is rigid with said trough 8 and forms a part of the conveyor unit A¹. Rigidly formed with the fuel inlet branch of the elevator unit A² is a socket member 13. Between the elevator unit A² and the conveyor unit A¹ is the transfer unit A³, comprising telescopically related tube sections 14, 15. A spherical ball 16 is formed at one end of the tube section 14 and is received in the socket member 12, while the spherical ball 17 of the tube section 15 is received

in the socket member 13 of the elevator unit A².

Each socket member 12, 13 is semi-annular in form and is provided with a diagonally disposed flange 24 to which is secured by a similar flange a cap or cover 23. The cap or cover 23 is also spherically shaped interiorly and fits over the respective ball 16, 17 of the tube section 14, 15 whereby the transfer unit A³ may move angularly in all directions and at the same time provide for the fore and aft movement which occurs during normal operation of the locomotive and tender. Rotative movement of the transfer unit A³ about its axis is restrained by providing each spherical ball 16, 17 with a lug 26 which projects through an elongated opening or slot 25 in each cover 23.

It will be observed from Fig. 3 that the lug 26 is directed outwardly from its respective ball 16, 17 at right angles to the plane of the flange 24. Thus, the cover 23 may be removed from its position over the spherical ball 16 or 17 by lifting the cover at a slight angle upwardly and laterally. By this construction, removal of the cover 23 is possible without interference of the tender and locomotive decks; at the same time, the ends of the transfer unit A³ are supported in the semi-annular spherical socket member 12, 13 upon removal of the cover 23.

Within the transfer unit A³ is the helical conveyor screw 18, which is coupled at its rear end 30 to the forward end of the conveyor screw 9 by means of a universal joint 19 and which conveyor screw 18 is suitably journaled at its forward or free end in the spherical ball portion 17 of the tube section 15.

In the gear box 11 is a set of gearing comprising a drive gear 27 coupled by a jointed or flexible drive shaft 28 with a drive motor 29 on the tender, a primary driven or transmission gear 30 on a shaft 31 driven by intermediate gearing 40 from gear 27, which shaft 31 is coupled to and drives the feed conveyor screw 9, and a second driven or transmission gear 32 driven by intermediate gearing from shaft 31 and which is coupled to a jointed or flexible conveyor drive shaft 33. The ratio of the gearing in the gear box is preferably such that in the case of a two-cylinder double-acting motor 29 of approximately 500 R. P. M., the screw 9 will have a ratio of 1 to 20 R. P. M. of the motor, shaft 33 thus being driven at a rate of speed from 20 to 25% faster than the screw 9. Shaft 33 drives a flexible transmission shaft 34 comprising sections 35 and 36 which are telescopically connected, section 35 being universally jointed to shaft 33 and section 36 being similarly jointed to the primary screw conveyor section 37 of a divided screw conveyor, including a delivery conveyor section 38, forming part of the elevator unit A². Shaft 34 thus comprises members jointed to swing vertically or laterally like the parts of connection A³ to compensate for similar relative movements of the locomotive and tender and to slide on each other to compensate for relative longitudinal movements of the locomotive and tender. It will thus be understood that shaft sections 35 and 36 of shaft 34 constitute in effect auxiliary portions of the transfer unit A³, disposed respectively on the tender and locomotive, and which are adapted to pull apart for separation, like the conduit sections 14 and 15, on the movement away from one another of the locomotive and tender, when said locomotive and tender are uncoupled, to effect a rapid, convenient and easy disconnection of the stoker units on the

35

65

70

75

locomotive and tender without the necessity of manually unfastening any parts thereof, the manifold advantages of which will be readily apparent to those versed in the art.

5 The elevator unit A² comprises a conduit 39 extending upwardly at an angle from its lower rear or receiving end, which is below the deck 2, through said deck and having its delivery end extending within the firing opening 4 and associated with a distributor 40, whereby the fuel is distributed over the area of the locomotive firebox. In accordance with my invention, the upper or delivery end of the conduit 39 is in the form of a single tube, within which the delivery 10 feed screw section 38 is arranged, while the lower or receiving end of said conduit is flared and forked and otherwise shaped to provide downwardly diverging branches or limbs 41 and 42 which are in open communication with each 15 other and merge into the lower portion of the delivery end of the conduit. The branch or limb 41 is coupled to the transfer unit or connection A³, for the feed of the fuel thereinto at one side of and upwardly and laterally toward the feed 20 screw section 37, which is disposed at an angle to the feed screw section 38 in the branch or limb 42 and extends outwardly therefrom and is coupled to the shaft 34, whereby the elevator 25 feed screw composed of the flexibly connected 30 and angularly arranged members or sections 37 and 38 is driven at the same rate of speed as the shafts 33 and 34. By this construction the conveyor screw branch 42 and fuel inlet branch 41 of the elevator conduit are arranged side by side 35 and in the same horizontal transverse plane, so as to provide for the feed of the fuel horizontally and laterally thereinto and in engagement with the elevator screw, so that said conduit portions will occupy a comparatively small amount of 40 vertical space and may thus be mounted on a locomotive having minimum deck height, or in the contracted space beneath the deck 2 and between the same and the locomotive frame 1, as a result of which I provide a stoker which is 45 universally applicable to various sizes and types of locomotives having high and low decks within minimum and maximum ranges. This construction and arrangement of parts also provides for the mounting of the elevator conveyor for operation 50 from a common source of power by transmission means separate from and independent of the transmission means operating the feed conveyors 9 and 18, and of said conveyors being driven by a gearing of the type described of any 55 predetermined gear ratio, whereby the elevator conveyor may be driven at any speed desired relative to that of the feed conveyors and without being limited by the speed of the latter. Preferably, as set forth, the ratio of the drive 60 gearing in the drive box 11 is such that the elevator conveyor 37-38 will be driven at a rate of speed of from 20 to 25% faster than the feed conveyors 9 and 18, by which provision is made to prevent any possibility of congestion of coal 65 in the elevator conduit and for a feed delivery rate of the elevator conveyor greater than that of the feed conveyors. The inlet end of the conduit 39 is provided in its upper portion with an opening 43 normally closed by a door 44 which 70 may be opened whenever it is desired to gain access to such portion of the conduit for the purpose of loosening up fuel therein or cleaning or repairing the elevator screw sections or for the use by the fireman to shovel coal therein for 75 delivery by the conveyor 37-38 in the event

that the conveyors 9 and 18, or either of them, should become broken or otherwise inoperative. The increased rate of speed of the conveyor 37-38, with respect to the conveyors 9 and 18 adapts the conveyor 37-38, because of its faster 5 rate of speed than the other conveyors, to be used for emergency purposes to deliver with the amount of coal being fed up by the conveyors 9 and 18, an additional amount shoveled into the conduit 39 by the fireman for the purpose of 10 augmenting the supply of fuel to the firebox when desired or required, or on occasions where the coal contains a high percentage of large lumps and sufficient coal can not be handled by the conveyors 9 and 18, in which case the fireman may overcome the difficulty by shoveling sufficient coal to make up that required to feed the locomotive through the opening 43 into the conduit 39. It often occurs on locomotives in 15 passenger service, which are coaled with a high percentage of large lump coal, that in coaling the locomotive tender a large proportion of the lump coal collects at the coal gates and at the forward end of the conveyor trough 8, making it at times very difficult to obtain the feed of a 20 sufficient amount of coal for consumption through the conveyor system. My invention overcomes this difficulty, as it allows manual stoking to be used in conjunction with automatic stoking, and in a very simple manner convenient to the fireman, and a mechanical stoker of great flexibility to suit varying conditions of service is thus furnished, since, in the event of 25 deficient feeding, or of maximum stoking being required, the amount of coal supplied to the firebox may be augmented by hand action, while, even in the event of the conveyors 9 and 18 becoming broken or inoperative, the conveyor 37-38 may be employed in conjunction with hand 30 feeding to furnish an ample supply of fuel to 35 the locomotive.

In the form of my invention shown in Figs. 1 and 2 the lower and upper portions of the conduit 39 are preferably arranged at an angle to each other, the lower portion extending upwardly toward the deck at a comparatively gentle angle and the upper portion extending upward through the deck and to the firing opening at a greater angle, in order to allow the lower conduit portion to be so disposed below the deck 2 45 that the opening 43 and its door 44 may be disposed in the plane of or flush with the deck, which will be found desirable under some conditions of use. The distributor 40 may be of any suitable construction, that shown being of 50 that type comprising a distributor plate 45 having diverging feed ribs 46 for spreading fuel on its feed to the firebox and associated with a steam jet device 47 for forcing the fuel over the distributor plate for supply to the full area of 55 the firebox. The unit A², like the unit A', is rigidly mounted and suitably secured against movement in the firing opening and to the back-head or frame of the locomotive by suitable tie rods or connections 48.

In the form of my invention shown in Figs. 5 and 6, the construction is substantially the same as that disclosed in Figs. 1 to 3, inclusive, except that there is a slight modification in the construction and form and arrangement of the conduit and elevator screw of the elevator unit A². As shown, in this construction the upper portion of the conduit 39' is disposed at an outward and rearward lateral angle to the central 70 vertical longitudinal plane of the unit A² and is 75

offset laterally with respect to the central vertical longitudinal plane bisecting the locomotive and tender, so as to dispose the upper portion of the conduit in axial alinement with the branch 42', while the branch 41' is offset laterally in the opposite direction to branch 42' from the central longitudinal plane to permit the same to be disposed in axial alinement with the transfer conduit of the transfer unit A³.
 10 With this arrangement the conveyor trough 8 may be arranged at the lateral angle shown in Fig. 1, or it may be disposed parallel with but at one side of the central longitudinal plane of the locomotive and properly connected to the branch 15 41', while such construction of the conduit permits of the substitution for a conveyor made of two screw sections 37 and 38 by a conveyor consisting of a single screw section 38', thus simplifying the structure in this respect. In this 20 construction, also, the conduit 39', as shown in Fig. 5, may be longitudinally straight, or with its upper and lower portions extending upwardly at the same angle. This arrangement is suitable 25 for locomotives having decks of adequate height or in which the fuel feed opening 43' and its top 44' may be disposed in an inclined plane extending slightly above the deck surface. The construction and operation of this form of stoker is otherwise the same as that disclosed in Figs. 30 1 to 3, inclusive.

In Fig. 7 I have shown at the delivery end of the elevator unit a distributor 40' of somewhat modified construction. This distributor preferably comprises a distributor plate 45' having a plane upper surface, dispensing with the ribs 46, and in which the steam jet device 47' is provided with nozzles having upper jet orifices 47^a and lower jet orifices 47^b. The function of the upper jet orifices is to sweep the fuel across the distributor plate, while that of the lower jet orifices is to dislodge any fuel which may fall into the spaces between the nozzles and to sweep the same across the distributor plate.

When the back wall of the boiler expands, it is necessary to have a movable connection between the deck 1 of the locomotive and the rear end of the conduit A². I have shown such connection in Fig. 9 in which the reference numeral 49 designates a casting having upwardly and inwardly extending lugs 50, 51, under the inwardly extending portion of which is a slideway 52. Suitably secured to the rear end portion of the conduit A² is a casting 53 at the bottom of which are outwardly extending flanges 54, 55 which are designed to slide in the slideways 52 so that the conduit A² is free from a rigid connection with the deck of the locomotive and is also free to slide independently of the locomotive deck when the rear wall of the boiler expands.

60 From the foregoing description, taken in connection with the drawings, the construction, mode of operation and advantages of my improved mechanical stoker will be readily understood by those versed in the art without a further and extended description. While the construction disclosed is preferred, it will, of course, be understood that changes in the form, proportions and arrangement and details of construction of the parts may be varied to degrees desired or required within the scope of the appended claims, without departing from the spirit or sacrificing any of the advantages of the invention.

75 I claim:—

1. In a locomotive stoker, the combination with a feed conduit, and a feed conveyor therein, of an elevator conduit having a delivery end and a receiving end, the latter end having communicating branches arranged side by side, a transfer conduit between said feed conduit and said elevator conduit, a socket member rigidly carried by one branch of the receiving end of said elevator conduit, a spherical ball carried by one of said tube sections at one end of said transfer conduit, such spherical ball being received in the socket member of said elevator conduit, a spherical ball carried by the other of said tube sections at the opposite end of said transfer conduit, the last named spherical ball being received in the socket member of said feed conduit, a cover fitted over each spherical ball and secured to a respective socket member, each cover and spherical ball being inter-engaged to restrain each tube section against movement about the axis of said transfer unit, each socket member arranged to support the respective ball member upon removal of the aforesaid cover from its position over its respective ball member, said socket member and cover being arranged whereby the ball member may be removed from its respective socket member upon removal of the cover thereover.

2. In a locomotive having a firebox provided with a back wall having a firing opening therein, and a tender, means for transferring fuel from said tender to said locomotive firebox comprising an elevator conduit fixed on the locomotive, said conduit being inclined forwardly and upwardly to the firing opening and having its lower end provided with branches offset laterally toward opposite sides of the locomotive, a conveyor unit including a trough mounted on the tender and arranged angularly with reference to the central vertical plane of the locomotive and tender, and an intermediate conduit section jointed at its rear end in end to end relation with said trough, and at its forward end jointed to one of the branches of said elevator conduit, gearing at the rear of said trough, a conveyor screw in the elevator conduit extending into the other branch thereof, a conveyor screw in said trough and a conveyor screw in said intermediate conduit, said conveyor screws being operatively connected with said gearing, and power means for driving said gearing.

3. In a locomotive stoker, a conveyor conduit on the locomotive having a forward portion lying in the central vertical plane of the locomotive and a rear portion comprising branches extending on opposite sides of said plane, a conduit on the locomotive tender having its rear end disposed in the central vertical plane of the locomotive and tender and said conduit thence extending forwardly at an angle with respect to the aforesaid central vertical plane of the locomotive and tender, an intermediate conduit flexibly connecting the forward end of the conduit on the tender with one of the branches of the conduit on the locomotive and at one side of the central vertical plane of the locomotive and tender, a conveyor in each of said conduits, the conveyor in the conduit on the locomotive including a section disposed in its branch lying at the opposite side of the central vertical plane of the locomotive and tender, gearing at the rear end of the conduit on the tender for driving 75

the conveyor therein and the conveyor in the intermediate conduit, and driving means connecting said gearing with the portion of the conveyor in the conduit on the locomotive disposed in the 5 second-named branch thereof.

4. In a locomotive stoker, a conveyor conduit on the locomotive having a forward portion lying approximately in the central vertical plane of the locomotive and tender, and a rear portion 10 comprising branches arranged side by side and extending in opposite directions with reference to such plane, a conduit on the locomotive tender having its rear end disposed on the central vertical plane of the locomotive and tender, said 15 conduit thence extending forwardly and laterally at an angle to such plane, an intermediate conduit flexibly connecting the forward end of the conduit on the tender with one of the branches of the conduit on the locomotive at one side of the central vertical plane of the locomotive and tender, a conveyor in the conduit on the locomotive and its other branch, conveyors in the 20 conduit on the tender and the intermediate conduit, gearing at the rear end of the conduit on the tender for driving the conveyor therein and the conveyor in the intermediate conduit, and driving means connecting said gearing with the portion of the conveyor in the conduit on the locomotive disposed in the second-named branch 25 thereof.

5. In a locomotive stoker, a conveyor conduit on the locomotive having a forward portion lying approximately in the central vertical plane of the locomotive and tender and a rear portion 30 comprising branches arranged side by side and extending in opposite directions with reference to such plane, a conduit on the locomotive tender having its rear end disposed on the central vertical plane of the locomotive and tender, said 35 conduit thence extending forwardly at an angle to such plane, an intermediate conduit flexibly connecting the forward end of the conduit on the tender with one of the branches of the conduit on the locomotive at one side of the central vertical plane of the locomotive and tender, a conveyor in the conduit on the tender, a conveyor in the intermediate conduit flexibly coupled thereto, a conveyor in the conduit on the locomotive comprising flexibly connected sections disposed in the forward portion of said 40 conduit and its other branch respectively, gearing at the rear end of the conduit on the tender for driving the conveyor therein and the conveyor in the intermediate conduit, and driving means connecting said gearing with the section of the conveyor in the conduit on the locomotive disposed in the second-named branch thereof.

6. In a locomotive stoker, the combination with a locomotive and its tender, said locomotive having a firing opening and a deck, an elevator conduit on the locomotive having a forward portion extending upwardly at an angle through the deck to the firing opening and having a rear portion located beneath the locomotive deck and provided with branches arranged side by side and on opposite sides of the central vertical plane of said conduit, said branch portions of the conduit being provided with a fuel inlet opening extending through said deck and a cover member 50 lying when in closed position substantially in the plane of the deck and forming a separable part thereof, a conduit on the tender, an intermediate conduit flexibly connecting the forward end of the conduit on the tender with one of the branches of the conduit on the locomotive, 55

flexibly connected conveyors in the conduit on the tender and the intermediate conduit, gearing at the rear end of the conduit on the tender for driving said conveyors, a conveyor in the conduit on the locomotive comprising flexibly connected sections arranged respectively in the forward portion of said conduit and in the other branch thereof, and driving means connecting said gearing with the section of the conveyor in the conduit on the locomotive disposed in the second-named branch thereof.

7. In a stoker for an intercoupled locomotive and tender, the combination including a conduit mounted on the locomotive, a conduit on the tender, and an intermediate conduit between said conduits, a socket member rigidly carried by the rearward end of said first named conduit, a socket member rigidly carried by the forward end of said second named conduit, said intermediate conduit including a pair of telescopically related tube sections, a spherical ball carried by one of said tube sections at one end of said intermediate conduit, such spherical ball being received in the socket member of said first named conduit, a spherical ball carried by the other of said tube sections at the opposite end of said intermediate section, the last named spherical ball being received in the socket member of said feed conduit, a cover fitted over each spherical ball and secured to a respective socket member, and means engaging each ball member for restraining each tube section against movement about the axis of said intermediate conduit, each socket member arranged to support the respective ball member upon removal of the aforesaid cover from its position over its respective ball member, each socket member and cover being arranged whereby the ball member may be removed from its respective socket upon removal of the cover thereover.

8. In a stoker for an intercoupled locomotive and tender, the combination including a conduit mounted on the locomotive, a conduit on the tender, and an intermediate conduit between said conduits, a socket member rigidly carried by the rearward end of said first named conduit, a socket member rigidly carried by the forward end of said second named conduit, said intermediate conduit including a pair of telescopically related tube sections, a spherical ball carried by one of said tube sections at one end of said intermediate conduit, such spherical ball being received in the socket member of said first named conduit, a spherical ball carried by the other of said tube sections at the opposite end of said intermediate section, the last named spherical ball being received in the socket member of said feed conduit, a cover fitted over each spherical ball and secured to a respective socket member, and means engaging each ball member for restraining each tube section against movement about the axis of said intermediate conduit, each socket member arranged to support the respective ball member upon removal of the aforesaid cover from its position over its respective ball member, each socket member and cover being arranged whereby the ball member may be removed from its respective socket by an upward and lateral movement upon removal of the cover thereover.

9. In a conduit system, a flexible joint structure comprising a rigidly supported spherical socket member, said socket member having spherical sides which terminate in a diagonal plane passed through the longitudinal axis of

- said socket member, a spherical ball seated in said socket member, and a cover over said spherical ball secured to said socket member for restraining movement of said spherical ball longitudinally of said socket member.
10. In a conduit system, a flexible joint structure comprising a rigidly supported spherical socket member, said socket member having spherical sides which terminate in a diagonal plane passed through the longitudinal axis of said socket member, a spherical ball seated in said socket member, a cover over said spherical ball secured to said socket member for restraining movement of said spherical ball longitudinally of said socket member, and means for restraining said spherical ball against movement about the longitudinal axis of said socket member.
11. The combination with a locomotive having a firebox with a firing opening therein and a tender for said locomotive provided with a fuel bin, of means for transferring fuel from said fuel bin to said locomotive firebox comprising a conduit system extending from the tender fuel bin to the firing opening in the locomotive firebox, conveying means in said conduit system for urging fuel therethrough including a conveyor screw system receiving fuel from the tender fuel bin and arranged to advance it forwardly, the fuel delivery end of said conveyor screw system being at one side of the vertical medial plane of the locomotive and tender, a conveyor screw system for advancing fuel toward the firing opening of said locomotive firebox, the rearward end of said conveyor screw system arranged to receive fuel from the forward end of the first named conveyor screw system and being offset laterally therefrom, and means for driving said conveyor screws including gearing operatively connected to the rearward end of the first named conveyor screw system, a prime mover at the side of the vertical medial plane of the locomotive and tender opposite to the laterally offset rearward end of the second named conveyor screw system, means operatively connecting said prime mover and said gearing, and a shaft oper-

atively connected with said gearing for transmitting power to the rearward end of the second named conveyor screw system, said shaft throughout its length being disposed laterally with respect to the first named conveyor screw system and on the side thereof opposite said prime mover.

12. The combination with a locomotive having a firebox with a firing opening therein and a tender for said locomotive provided with a fuel bin, of means for transferring fuel from said fuel bin to said locomotive firebox comprising a conduit system extending from the tender fuel bin to the firing opening in the locomotive firebox, conveying means in said conduit system for urging fuel therethrough including a conveyor screw system receiving fuel from the tender fuel bin and arranged to advance it forwardly, the fuel delivery end of said conveyor screw system being at one side of the vertical medial plane of the locomotive and tender, a conveyor screw system for advancing fuel toward the firing opening of said locomotive firebox, the rearward end of said conveyor screw system arranged to receive fuel from the fuel delivery end of the first named conveyor screw system and being offset laterally therefrom at the opposite side of the vertical medial plane of the locomotive and tender, and means for driving said conveyor screws including gearing operatively connected to the rearward end of the first named conveyor screw system, a prime mover at the side of the vertical medial plane of the locomotive and tender opposite to the laterally offset rearward end of the second named conveyor screw system, means operatively connecting said prime mover and said gearing, and a shaft operatively connected with said gearing for transmitting power to the rearward end of the second named conveyor screw system, said shaft throughout its length being disposed laterally with respect to the first named conveyor screw system and on the side thereof opposite said prime mover.

WASHINGTON T. CAPPS.

45
